W. G. Bush

UNITED STATES PATENT OFFICE.

WALTER G. BUSH, OF POUGHKEEPSIE, NEW YORK.

PISTON RING.

Application filed February 8, 1923. Serial No. 617,810.

To all whom it may concern:

Be it known that I, WALTER G. BUSH, a citizen of the United States, residing at Poughkeepsie, in the county of Dutchess 5 and State of New York, have invented certain new and useful Improvements in Piston Rings; and I do declare the following to be a full, clear, and exact description of the invention, such as will enable others skilled in the art to which it appertains to make and use the same.

My invention relates to improvements in piston rings and has for its principal object to provide a simple and inexpensive 15 ring designed primarily for use in connection with aluminum pistons and so constructed that its inherent resiliency is not relied upon to expand it within the cylinder, thus enabling the use of bronze or other soft 20 metal in the manufacture of the ring so that there is no danger whatever of scoring the cylinder wall.

The ring is formed of four sections which break joints with each other and a further 25 object is to provide novel connecting means between these sections whereby forcing two of them outwardly under spring pressure, will transmit similar movement to the other sections, forming a tight contact with the 30 cylinder wall while permitting relative movement of the sections in adapting them to worn cylinders.

Another object is to provide connecting 35 means between the ring sections which, while permitting assembly of these sections in the ring groove and removal thereof when necessary, will not permit accidental removal of the ring when the piston is out of the cylinder.

With the foregoing in view, the invention resides in the novel subject matter hereinafter described and claimed, the description being supplemented by the accompanying drawing.

Figure 1 is a horizontal sectional view 45 showing a ring constructed in accordance with the present invention, applied to a piston and cylinder.

Figure 2 is an edge view of the ring. 50 Figure 3 is a vertical sectional view as indicated by line 3—3 of Fig. 1.

Figure 4 is a disassembled plan view of the ring, showing more particularly the formation of its several sections.

In the drawing above briefly described, 55 the numerals 1 designate a pair of substan-

tially flat semi-circular ring sections disposed in the same plane with their ends contiguous to each other, the inner edges of said sections being formed with recesses 2 in which springs 3 are mounted to engage the bottom of the ring groove and force the two sections outwardly away from each other for tight contact with the cylinder wall. To guide the sections in this movement, they are each preferably provided with a central radial rib 4, these ribs being received in grooves 5 formed in one side of the ring groove. The springs 3 are preferably of bowed form and they may well be 70 secured to the ring sections 1 by having inwardly extending integral feet 6, secured by appropriate fasteners 7 to the inner ends of the ribs 4, which ends may extend beyond the walls of the recesses 2, for this 75 purpose.

Contacting with one flat radial side of the sections 1 and breaking joints with these sections, are two additional sections 8 which are of arcuate form but are preferably 80 somewhat shorter than the sections 1. The central portions of these sections 1, are preferably thickened as indicated at 9 between the ends of the two sections 8, in order to prevent chattering of said central portions 85 in the ring groove. These thickened portions will also prevent any excessive turning of the sections 8 circumferentially of the sections 1.

As above described, means are provided 90 for forcing the ring sections 1 radially outward and I make novel provision whereby this movement is imparted also to the ring sections 8, without the use of additional springs for these last named sections. In 95 the present showing, the sides of the sections 1, with which the sections 8 contact, are formed with circumferentially extending grooves 10 adjacent the ends of the sections 1. The ends of the grooves 10 remote from 100 the ends of the ring sections 1, preferably open laterally through the peripheries of said sections as indicated at 11 in order that projections 12 on the inner faces of the ring sections 8, may enter the grooves 10 through 105 said portions 11, when assembling the ring, and may pass outwardly through said groove portions when disassembling.

When the ring is assembled and the sections 1 are forced outwardly by the springs 3, the inner side walls 13 of the grooves 10 thrust against the projections 12 of the 110

sections 8, thereby providing co-operating shoulders which transmit the radial movement of the sections 1 to the sections 8. Thus, the entire ring is expanded for tight contact with the cylinder wall and relative movement of the several sections, is permitted, thus allowing the ring to be readily adapted to uneven cylinder walls.

The ring may be used on numerous kinds 10 of pistons, but is well adapted for aluminum or other light metal constructions. The several sections of the ring may well be formed of very soft material, as separate springs are provided for expanding these 15 sections against the cylinder wall, instead of relying on any inherent resiliency of the metal. One advantage of this soft metal formation, is that there is no possibility of scoring the cylinder wall. Other advantages 20 for the construction shown, are that a leak proof ring is provided and one which will effectively prevent side slap of aluminum or other comparatively light pistons.

As excellent results may be obtained from 25 the details disclosed, they may well be followed. However, within the scope of the invention as claimed, numerous minor changes may be made.

I claim:

30 1. A piston ring comprising a pair of diametrically opposed substantially semi-circular ring sections in a common plane, spring

means for forcing said sections outwardly away from each other on a diametrical line, one radial side of each ring having an 35 L-shaped groove near each of its ends, one end portion of said groove being disposed circumferentially of the ring section, while the other end portion of such groove opens through the peripheral edge of said section, 40 a second pair of arcuate ring sections contacting with said radial side of said first named sections and breaking joints therewith, and projections on said second pair of arcuate ring sections, said projections being 45 slidably received in the first named end portions of said L-shaped grooves.

2. A piston ring including a pair of substantially semi-circular ring sections disposed in a common plane and provided with 50 central radially disposed ribs on one side, said ribs extending beyond the inner portions of the sections, said portions having circumferentially elongated recesses, and bowed springs positioned in said recesses to 55 engage the bottom of the ring groove and force the ring sections outwardly, said springs having inwardly extending feet secured to the inwardly projecting ends of 60 said ribs.

In testimony whereof I have hereunto affixed my signature.

WALTER G. BUSH.
